UNITED STATES PATENT OFFICE.

PETER RUBINOVITCH, OF BOSTON, MASSACHUSETTS.

SLEEPING-CAR BERTH.

936,814.

Specification of Letters Patent.

Patented Oct. 12, 1909.

Application filed October 19, 1908. Serial No. 458,378.

To all whom it may concern:

Be it known that I, PETER RUBINOVITCH, a subject of the Empire of Russia, residing at Boston, in the county of Suffolk and 5 State of Massachusetts, have invented certain new and useful Improvements in Sleeping-Car Berths, of which the following is a specification.

This invention relates to an improvement 10 in sleeping car berths and has for its object, to construct a berth, which is adapted to turn up into a vertical position with a sliding bar and a movable support jointed at their inner ends to a sleeve fixed to the 15 compartment partition and directly to the compartment partition, respectively, and with said bar at its outer end adjustably connected with said support; and which is also adapted to turn down into an extended 20 position by extending said bar and support and locking them together, so that the berth shall be supported in its extended position, without the aid of any supports resting on the floor or other supports fixed to the berth 25 frame or to the sides of the compartment of the car.

In the accompanying drawing, Figure 1. represents a side elevation of my improved 30 berth in its turned up or vertical position, also a portion of the berth frame; Fig. 2. is a plan view of the bottom of the upper part 35 of the casing; Fig. 3. is a perspective view in its extended position; Fig. 4. is a front elevation in partial section; Fig. 5. is a cross section of a compartment in a sleeping car, with the berth in its extended position.

Referring to the different figures, A. represents a sleeve fastened to the compartment 40 partition C. of the car by means of the screws, a. a. Pivoted at one end to this sleeve by means of the bolt b. is a bar B. having sliding engagement at its other end with the berth frame E. by means of trunnions b' b'. on either side of the bar engaging 45 internal grooves e⁵, of a longitudinal slot e⁴ of the berth frame E. The berth frame E. is pivoted to the section partition C. at e, by means of a hinge member e⁸ fastened to the bottom, or preferably to the 50 side, of the berth frame by means of the screws e'.

Fastened to the upper side of the bar B. is a casing D. composed of a flat plate d' 55 surmounted by a box shaped portion d, the two portions being fastened together by screws d², in holes d¹⁵ (Fig. 2), and the plate

being fastened to the bar B. by means of screws d¹⁶. In the space between these two members of the casing is slidably mounted a latch plate d⁶, having a widened 60 lower extremity d⁹ adapted to engage a notch e² in the top face of the berth frame member E. In order to withdraw the latch plate from engagement with the notch e², a rock lever d⁸ forked at its lower end is pivoted on the transverse pin d⁴ fastened across a slot d⁵ in the member d of the casing, the forked ends being adapted to engage on either side a transverse pin d⁷ bridging a slot d⁸ in the latch plate. It is evident from 65 Fig. 4, that a downward pressure on the outer end of the lever d⁸ will cause the lever to rock about the pin d⁴, so that one of the forked ends will engage the pin d⁷ and move the latch plate out of engagement with the 70 notch. In order to hold the latch plate yieldably in either its operative or retracted position, a latch pin d¹³ pressed outwardly by a coiled spring d¹⁴ is provided in the bar B. This pin passes through a perforation 75 in the plate d' and its rounded outer end is adapted to seat itself in one of two depressions d¹², on the under side of the latch plate d⁶, when the latch plate is in its engaging or retracted position. On a movement of 80 the lever d⁸, however, the pin is wedged inwardly against the spring d¹⁴ by the inclined face of one depression thus allowing the latch plate to move freely till the end of the pin may engage the other depression. 85

At e³ in the berth frame E. forward of the butt e⁷ is a hole opening into the internal slot e⁴ and used for the removal of dust from the slot when the support E is raised up. The figures represent the fittings at one side 90 only of the bar B. and of the berth frame E. When the berth is in an inclined and extended position, as shown in Figs. 3, 4, and 5, the bar B. is pivoted at one end to the sleeve, by means of the bolt, b. and the catch 95 d⁶. is slidably engaged with the notch e², in the end of the berth frame E., so that the berth is securely fastened together.

To turn the berth up into a folded and vertical position, first withdraw the catch 100 d⁶ from the notch e², by pressing forward the rock lever d⁸, then raise the outer end e⁶ of the berth frame E., on the bolts b and e, while the pointed end b² and the trunnions b' b'. of the bar B. move forward and upward in the internal grooves e⁵, in the longitudinal slot e⁴ from the butt e⁷ toward the 110

outer end e^6 , of the berth frame E. until the berth is folded together in a vertical position, against the section C. of the compartment of the car.

5 Claims.

1. A sleeping car berth comprising a sleeve fixed to the berth frame, a sliding bar and a movable support fixed to the inside of the berth-frame, and jointed at their inner 10 ends, to said sleeve and berth frame, respectively, said bar having a pointed end and two trunnions placed opposite each other, at its outer end, and said support having a butt, a dust hole and a transverse slot at 15 its inner end, a longitudinal slot and interior grooves in its central part, and, an outer end opening, and said pointed end and trunnions being adapted to run in said longitudinal slot and grooves, respectively, 20 and, a casing fixed to the top and outer end of the bar and having a rock lever and a slidible catch connected together in a recess therein; said catch being adapted to fit into said transverse slot and lock the berth, 25 when it is extended, and the same to be withdrawn from said transverse slot, when the berth is to be turned up into a vertical position, substantially as set forth.

2. In a sleeping car berth, the combination 30 with a berth frame, of a sleeve fixed to same,

a sliding bar jointed, at its inner end, to said sleeve and having a pointed end and two trunnions placed opposite each other at its outer end, a casing fixed to the top of the outer end of the bar and having a rock lever 35 and a slidable catch connected together in a recess therein and a movable support fixed to the inside of the berth-frame and jointed, at its inner end to the berth frame and having a butt, a dust hole and a transverse slot, 40 at its inner end, a longitudinal slot and internal grooves, in its central part, and an outer end opening; said pointed end and trunnions being adapted to run back in said longitudinal slot and grooves, respectively, 45 and, said catch, to fit into said transverse slot and lock the berth together, when the berth is extended; and said catch, to be withdrawn from said transverse slot and said pointed end and trunnions, to run forward, in said longitudinal slot and grooves, 50 when the berth is lifted into its vertical position, substantially as described.

In testimony whereof I affix my signature in presence of two witnesses.

PETER RUBINOVITCH.
